2,128,017

CIGAR LIGHTER

John Sinko, Chicago, Ill.

Original application May 10, 1934, Serial No. 724,849. Divided and this application August 15, 1936, Serial No. 96,274

9 Claims. (Cl. 219—32)

This invention relates to electric cigar lighters of the type used on automobiles and more particularly to those commonly known as wireless lighters because the igniting plug may be removed from the base or holder and used for lighting a cigar, cigarette, or pipe without maintaining electrical connection with the socket member.

In the embodiment illustrated the igniting unit is removably held in the socket with one of its terminals out of electrical contact with the base-contact member in the socket, but by pressing the plug into the socket against a spring resistance, the circuit is closed through the heating element and when the pressure on the plug is released it automatically opens the circuit and the igniting plug is ready for use.

One of the objects of the invention is to provide an improved lighter of the above character, simple in construction, inexpensive to manufacture, and positive in operation.

A further object of the invention is to provide an improved switch or contact unit in the socket member wherein a movable contact member or sleeve is always kept in electrical contact with a source of current supply without relying upon a sliding contact.

A further object of the invention is to provide a fixed base-contact member in the socket which is secured against rotation so that in the event the igniting plug is twisted while in contact therewith to improve the electrical connection, the base-contact member will not turn or become loose.

The present application is a division of my application No. 724,849, filed May 10, 1934.

The invention is illustrated in a preferred embodiment in the accompanying drawing, in which—

Figure 1 is an assembled view showing the assembled socket casing and igniting plug; Fig. 2 a broken elevational view showing how the igniting plug fits into the casing; Fig. 3 a vertical sectional view through the assembly, taken as indicated, at line 3 of Fig. 1; Fig. 4 a sectional view, taken as indicated, at line 4 of Fig. 3; Fig. 5 an elevational view showing the contact unit removed from the casing; Fig. 6 a sectional view, taken as indicated, at line 6—6 of Fig. 3; and Fig. 7 a sectional view, taken as indicated, at line 7—7 of Fig. 3.

In the embodiment illustrated A designates a tubular casing; B a contact unit secured in the inner end of said casing; and C a removable igniting plug adapted to fit into the casing and make electrical contact with the two terminals

of a source of electrical supply by means of the contact unit B.

The outer shell of the casing A may have an enlarged cylindrical portion 8 to permit light rays from the igniting element to travel out through an annular passage 9 to a transparent or translucent ring 10 which is secured to the casing by means of a shroud ring 11. An inner supporting sleeve 12 is shown carried by the ring 10 and may be provided with an inwardly extending yielding tongue 13 for pressing against the body of the plug to hold it frictionally within the socket. As shown in Figs. 1 and 2 the casing A may be further provided with ventilating apertures 14 to permit heat from the lighting element to escape.

The contact unit B is shown with an inverted cup shaped central post 15 whose lower end is turned outwardly and upwardly to form a flange 16 which serves as a seat for a compression spring 17. As shown in Figs. 3 and 5, ears 18 are struck out of the flange 16 and are adapted to fit into slots provided in a washer 19 which is secured to the inner end of the casing A by means of a bushing 20 which has its outer end turned over the inner marginal portion of the washer as indicated at 21. The bushing is shown provided with a lock washer 22 and a nut 23 for attaching the casing to the dashboard of the car by means of a yoke (not shown).

To the upper end of the post 15 is fixedly secured a contact spider 24 and is insulated from the post by means of an upper insulating washer 25 and a lower insulating washer 26, the assembly being firmly gripped by means of a hollow center stud 27 in which is secured a pigtail 28 leading to a source of electrical supply. The pigtail is provided with the usual insulation 29 below the stud and may be further protected by means of a fiber sleeve 30 extending into the bushing 20. A contact sleeve 31 provides a movable contact socket to receive the igniting plug C. The sleeve is provided with an inwardly extending flange 32 which is slidably mounted on the post 15 and is urged upwardly against the insulating disk 25 by means of the compression spring 17. The contact sleeve provides one of the connections with an electrical source and it will be noted that the spring maintains positive electrical contact with the same without relying on sliding connections or contacts which may occur with the casing A which is usually grounded to the dashboard of a car. Preferably the flange 16 makes a snug pressed fit with the lower portion of the casing A to hold the contact unit in

position, while the contact sleeve 31 is freely slideable within the casing.

- 5 The igniting plug C is shown provided with the usual handle or knob 33 which is secured to the conducting body portion 34 by means of a threaded coupling 35 which may be made of insulating material. The body portion 34 is shown provided with an annular shoulder 36 which is adapted to be engaged by the contact sleeve 31.
- 10 On the inner end of the body portion is provided a contacting cup shaped member 37 to which one end of the coil of resistance wire 38 is connected. The cup is held insulated from the body portion by means of insulating washers 39 and 40 and the other end of the coil 38 is secured to a center stud 41 which serves to grip the assembly together and connect the coil to the body portion 34.

15 As will be readily understood the plug is normally held in inoperative position as shown in Fig. 3, and by pressing upon the knob 33 against the tension of spring 17 the rim of the cup 37 may engage the contact member 24. This closes a circuit through the heating coil 38 traced from 20 the live conductor or pigtail 28, center stud 27, base-contact member 24, cup 37, heating element 38, stud 41, body member 34, contact sleeve 31, spring 17, flange 16, and the outer shell or casing A which is grounded to the dashboard of a car.

25 30 When the heating coil reaches incandescence, a condition which may be observed by glowing of the ring 10, the plug may be withdrawn for use.

35 The foregoing detailed description has been given for clearness of understanding only, and no unnecessary limitations should be understood therefrom, but the appended claims should be construed as broadly as permissible, in view of the prior art.

I claim:

- 40 1. In a cigar lighter: an elongated socket casing adapted to receive an igniting plug; an igniting plug adapted for insertion in said casing, said plug having an inwardly extending shank of conducting material provided with an annular shoulder, and said plug having at its inner end an ignition element with one end connected to said plug shank and the other connected to a contact-member mounted on and insulated from the plug shank; and a contact unit in the base of the 45 casing comprising a central post on which is mounted and insulated from the casing a base contact-member for engaging said plug contact-member, a spring actuated contact sleeve slidably mounted on said post but insulated from the base 50 contact-member and extending outwardly around the ignition element into engagement with the annular shoulder of the plug to maintain electrical connection with the ignition element and yieldingly maintain the base contact-member 55 and plug contact-member out of electrical engagement but permitting connection therebetween by manual pressure upon the plug to close the circuit for the ignition element.

60 2. In a cigar lighter: a fixed tubular casing adapted to receive an igniting plug; an igniting plug provided at its inner end with a cup contact-member in which is mounted a resistance wire having one end connected to said cup and the other end to a contactor on said plug insulated 65 from the cup; and a contact unit in the base of said casing comprising an outwardly extending fixed post on which is fixedly mounted an insulated base-contact member adapted to be engaged by said cup, a socket-sleeve slidably mounted in

said casing below said base-contact member and adapted to receive said plug and make contact with said contactor around the plug, and a spring on said post serving yieldingly to urge the socket sleeve outwardly to prevent contact between said 5 cup and base-contact member and serving to maintain electrical connection between said sleeve and tubular casing.

3. A device as specified in claim 2, in which the contact unit is provided with inwardly extending ears to engage slots at the end of the casing and prevent the unit from turning with respect thereto.

4. A device as specified in claim 2, in which the post is provided at its base with an annular 15 cupped flange to form a seat for the spring and make a press-fit connection with the side wall of the casing.

5. A device as specified in claim 2, in which the socket sleeve is provided with an inwardly extending flange encircling said post, and an insulating washer is fixedly mounted on the outer end of the post between base-contact member and post so as to limit the outward movement of said flange and prevent the sleeve from contacting the base-contact member.

6. A device as specified in claim 2, in which the base-contact member is in the form of a spider secured to said post by means of a hollow center stud in which is mounted a pigtail connected to 30 a source of current supply.

7. In a cigar lighter: a fixed tubular casing adapted to receive an igniting plug; an igniting plug provided at its inner end with a cup-shaped contact member in which is mounted a resistance wire having one end connected to said cup and the other end to a contactor on said plug insulated from the cup; a slotted washer mounted on the inner end of said casing so as not to rotate with respect thereto; and a contact unit in 40 the base of said casing comprising a contact terminal insulated from the casing and interlocked against rotation with respect thereto by means of ears projecting into said slotted washer whereby a clean electrical contact can be obtained by twisting 45 the cup-shaped contact on the plug thereagainst, and an electrical conductor extending through an end wall of the casing and having its end permanently connected to said contact terminal.

8. In a cigar lighter: a fixed tubular casing adapted to receive an igniting plug; an igniting plug provided at its inner end with a cup-shaped contact member in which is mounted a resistance wire having one end connected to said cup and 55 the other end to a contactor on said plug insulated from the cup; a slotted washer in the inner end of the casing; a bushing extending through the end wall of said casing and having its outer end turned over the inner marginal portion of 60 said washer to secure the washer in position; and a contact unit in said casing comprising a contact terminal mounted on an insulating washer and interlocked against rotation with respect to said casing by means of ears projecting into the 65 slots in said washer, and an electrical conductor extending through said bushing and insulated therefrom, said conductor having its end permanently connected to said contact terminal.

9. A device as specified in claim 8, in which the 70 bushing has an externally threaded shank in rear of the casing for securing the casing to the dashboard of a car.

JOHN SINKO.
